United States Patent Office

Des. 204,063
Patented Mar. 15, 1966

204,063

FLAG

Mae L. Roy, Box 23, Tewksbury, Mass.

Filed Feb. 11, 1965, Ser. No. 83,777

Term of patent 14 years

(Cl. D29—17)

FIG. 1 is a front elevational view of a flag, showing my new design, same being duplicated on the opposite side thereof, not shown.

FIG. 2 is a partial sectional view thereof, taken along the line 2—2, FIG. 1.

The essential features of the design reside in the portions shown in solid lines.

I claim:

The ornamental design for a flag, as shown and described.
